We claim the ornamental design for tag and lanyard assembly, as shown.

DESCRIPTION

FIG. 1 is a front perspective view of a tag and lanyard assembly according to an embodiment of the invention;

FIG. 2 is a rear perspective view of the tag and lanyard assembly according to FIG. 1;

FIG. 3 is a front perspective view of a tag and lanyard assembly according to an embodiment of the invention;

FIG. 4 is a rear perspective view of the tag and lanyard assembly according to FIG. 3;

FIG. 5 is a front perspective view of a tag and lanyard assembly according to an embodiment of the invention; and,

FIG. 6 is a rear perspective view of the tag and lanyard assembly according to FIG. 5.
